UNITED STATES PATENT OFFICE.

PIETRO BENINCASA, OF NEW YORK, N. Y., ASSIGNOR OF THIRTY PER CENT TO
ANTONIO TEDESCO, OF BROOKLYN, NEW YORK.

SHOE-SHINING MACHINE.

Application filed July 14, 1924. Serial No. 725,807.

To all whom it may concern:

Be it known that I, PIETRO BENINCASA, a citizen of the United States, residing at New York city, in the county of New York 5 and State of New York, have invented certain new and useful Improvements in Shoe-Shining Machines, of which the following is a specification.

This invention relates to a shoe shining 10 machine, having more particular reference to a machine of this type in which a number of rotary power driven brushes are provided and are arranged for manipulating by the operator to engage the shoe, the invention 15 having for an object the provision of a novel and improved machine of this sort which may be cheaply constructed.

For further comprehension of the invention, and of the objects and advantages 20 thereof, reference will be had to the following description and accompanying drawing, and to the appended claims in which the various novel features of the invention are more particularly set forth.

25 Fig. 1 of the drawing is a side view showing my improved machine.

Fig. 2 is a face view thereof.

Fig. 3 is a horizontal sectional view taken 30 on the line 3—3 of Fig. 2.

35 Fig. 4 is a detail view partly in elevation and partly in vertical section, showing the connection of the flexible shaft, at one end to the motor shaft, and at its other end to the brush.

40 As here embodied my improved machine comprises an upright frame consisting of the side posts 10 which rest at their lower ends on a suitable support which also carries the usual footrest. The upper ends of these posts have mounted thereon a casing 14 which projects laterally from the posts as shown in Fig. 1. Within this casing are two electric motors 15 which are mounted on generally vertical axes, being arranged to 45 have a slight pillatory movement, the motor casings being provided on opposite sides with the trunnions 16 which engage in bearing elements 17 fixed on the bottom of the casing, the motors being thus arranged to swing bodily on a horizontal axis. Each of these motors has connected to its rotor a flexible shaft 18 which extends downward and has a brush mounted on its lower end as will be presently set forth. The upper 50 portion of the shaft 18 passes through a

rigid tubular member 19 which is fixed at its upper end to the motor casing to swing with the latter, while this member has attached to its lower end a shorter flexible tubular member 19' through which the lower portion of the shaft 18 extends. Suitable slotted apertures 20 are provided in the bottom of the casing to accommodate the tubular members 19.

55 The flexible shafts are preferably connected to the brushes by universal joints as shown, each shaft being fixed to a head 21 from which one pair of the forked elements of the joint project, while the brush is attached to a spindle 22 from which the other forked element of the joint projects, these forked elements being attached to the usual ball 23. Formed on the spindle 22 are the vertically spaced flanges 25 between which the spindle is surrounded by a collar 26 from which a handle 27 projects. Projecting from this handle is a disk-like member 28 that has an aperture 29 therein through which the spindle 22 passes. Surrounding the lower portion of the lower flexible tubular element 19', and also the universal joint, is a coiled expansion spring 30 which bears at its upper end against a flange 31 on the lower end of the tubular member 19 and at its lower end on the member 28, this spring being normally under considerable compression, and closely surrounding the said flexible tube 19'. By means of this particular disposition of flexible tube, universal joint, and surrounding spring, the brushes may be readily adjusted to follow the contours of the shoe being shined, while at the same time tendency of the flexible shaft to vibratory or loose movement is prevented.

60 The brush is preferably mounted on the spindle 22 to be readily attached thereto and removed therefrom. As here shown the bristles, or cloth, or other portion 32 of the brush is mounted on a spool 33 which is engaged over the lower end of the spindle and is provided with an inwardly projecting pin 34 which engages in a bayonet slot 35 in the side of the spindle, the horizontal portion of said slot being turned in the proper direction to have the rotary movement of the brush act to keep the pin in place in the said horizontal portion of the slot and thereby hold the brush on the spindle. For controlling the motor fixed and movable contact members 37 and 38 may be 65 70 75 80 85 90 95 100 105 110 115

mounted on the handle 27 and provide a normally open switch which is readily closed by the hand of the operator.

A pair of hooks 50 may be mounted, one on each of the posts 10, to have the handles 35 hooked thereover to support the brushes when the machine is not in use. The casing 14 may be provided on the front with a hinged door 14', while on the opposite or rear side of the machine a wall member 55 extends between the posts 10 and has therein a hinged door 56 which, when thrown upward to permit of the customer placing his foot on the rest 12 may operate, through a plunger bar 57, a counting machine 58. On one side of the casing 14 may mount a money box 59 and on the other side a box 60 to contain a cleaning fluid such as gasoline. The wall of this box may be roughened on its inner face along one side to facilitate cleaning of the brush.

In the use of the machine, the customer places his foot on the rest 12, which is located midway between the sides of the machine. The operator grasps the handle 35 of the brushes and places the latter one on each side of the shoe, and moves the brushes back and forth along the shoe, the motors oscillating on their trunnions. The provision of the universal joints in the shafts 18 enables the brushes to be more readily inclined at such angles as may be necessary in working upon the shoe.

Having thus described my invention, what I claim as new and desire to protect by Letters Patent of the United States is as follows:

1. A shoe shining machine comprising a frame, a motor supported thereon, a flexible shaft attached at its upper end to said motor, and a brush on the lower end of the said shaft, said brush being attached to the shaft by a universal joint connection, and a resilient device preventing free angular adjustment of the brush with respect to the shaft.

2. A shoe shining machine comprising a frame, a motor supported thereon, a flexible shaft attached at its upper end to said motor, and a brush on the lower end of the said

shaft, said brush being attached to the shaft by a universal joint connection, and a resilient device preventing free angular adjustment of the brush with respect to the shaft, a collar freely engaged with said brush, and a handle fixed to said collar.

3. A shoe shining machine comprising a pair of posts, a casing fixed to the upper ends thereof, a pair of electric motors mounted in said casing on vertical axes, a pair of flexible shafts attached at their upper ends to the shafts of the said motors, and brushes removably mounted on the lower ends of said shafts.

4. A shoe shining machine comprising a frame, a motor supported on said frame for oscillatory movement on a horizontal axis, said motor having its rotor axis extending in a generally vertical direction, a flexible shaft connected at its upper end to the motor, and extending downward therefrom, and a brush attached to the lower end of said shaft.

5. A shoe shining machine comprising a frame, a motor supported on said frame for oscillatory movement on a horizontal axis, said motor having its rotor axis extending in a generally vertical direction, a flexible shaft connected at its upper end to the motor, and extending downward therefrom, and a brush attached to the lower end of said shaft and a tubular housing for said shaft consisting of an upper rigid portion and a lower flexible portion.

6. A shoe shining machine comprising a frame, a motor supported thereon, a flexible shaft attached at its upper end to said motor, and a brush on the lower end of the said shaft, said brush being attached to the shaft by a universal joint connection, and a resilient device preventing free angular adjustment of the brush with respect to the shaft, a collar freely engaged with said brush, and a handle fixed to said collar.

In testimony whereof I have affixed my signature this 31st day of May, 1924.

PIETRO BENINCASA.

In the presence of—
ERMINIO M. NETTI.
